UNITED STATES PATENT OFFICE.

ABRAHAM EBERHART, OF MIFFLINBURG, PENNSYLVANIA.

RAIL-TIE.

1,051,806.

Specification of Letters Patent. Patented Jan. 28, 1913.

Application filed October 8, 1912. Serial No. 724,570.

To all whom it may concern:

Be it known that I, ABRAHAM EBERHART, a citizen of the United States, residing at Mifflinburg, in the county of Union and State of Pennsylvania, have invented new and useful Improvements in Rail-Ties, of which the following is a specification.

This invention relates to rail ties and the object of the invention is to provide a simple 10 constructed and durable tie at a cost not greatly exceeding the cost of the ordinary wooden tie.

A further object of the invention is to provide a tie of this character so reinforced 15 that it will withstand all compressions and tensile strain and which will be effective to support rails properly irrespective of the number of cracks or breaks in the body of the tie.

20 Further objects of this invention will appear as the following specific description is read in connection with the accompanying drawing which forms a part of this application, and in which:—

25 Figure 1 is a top plan view of the tie with parts broken away to show one layer of the reinforcing material therein. Fig. 2 is a side elevation. Fig. 3 is a horizontal section taken on the line 3—3 of Fig. 2. 30 Fig. 4 is a vertical transverse section on the line 4—4 of Fig. 2. Fig. 5 is a similar section on the line 5—5 of Fig. 2. Fig. 6 is a perspective view of one of the locking blocks. Fig. 7 is a similar view of a locking 35 block used where fish or joint plates are used. Fig. 8 is a perspective view of the plate locking key used. Fig. 9 is a similar view of the spike. Fig. 10 is a perspective view of an adjustable locking block.

40 Referring more particularly to the drawings 1 represents the body of the tie which is preferably constructed of cement compounded in any approved manner. Embedded 45 in the tie adjacent the bottom thereof is a strip of wire fabric 2 the strands of which are of sufficient strength to properly reinforce the tie and to prevent separation of its ends should the cement body crack through the center. This reinforcement is 50 duplicated adjacent the upper side as shown at 3 and intermediate the fabric strips 2 and 3 there are embedded in the tie suitable reinforcing rods 4 which extend outwardly, beyond the tie in handle loops 5. Between 55 these rods and the upper and lower fabric

there is embedded in the body of the tie suitable plates 6 which have threaded apertures to receive the rail locking spikes and the plate locking keys to be hereinafter described.

60 In the construction of the device locking keys 7 and rail retaining spikes 8 are passed through rail supporting plates and positioned in a suitable mold with their threaded ends 9 arranged uppermost. A predetermined quantity of cement is then laid in the mold around the plates, keys and spikes and mounted upon this cement is the reinforcing fabric 3 through which the keys and spikes pass. Cement is then placed in 70 the mold until the same is approximately one-half filled when the rods 5 are mounted therein and the spike and key plates 6 threaded onto the ends of the spikes and keys before described. More cement is then 75 laid over these rods and nuts and another sheet of fabric 2 is embedded in a final layer of cement as shown. When the tie is partially hardened the spikes and keys are removed and when fully hardened the ties are 80 ready for shipment. In applying the rails the same are seated upon the supporting plates in the position shown in Fig. 2 and the spikes screwed down tightly with their heads overlapping the base of the rail as 85 is usual. Suitable locking blocks 10 are then placed in position on the tie and the keys 7 threaded in position to hold the blocks 10 against displacement. These blocks are 90 preferably constructed as shown with their side edges tapering or thinned out and provided with notches 11 to receive the spikes and with similar notches on the opposite side to receive the keys 7. The blocks may be made slightly wedge shape as shown in 95 Fig. 10 so that they are adaptable for either a seventy or eighty-five pound rail. The handles 5 projecting from the ends of the body form a convenient means for handling the ties and at the same time the rods upon 100 which these handles are formed provides a durable reinforcing structure. The blocks 10 and their associated locking keys 7 are provided to form a reinforced abutment for the spikes to prevent the same from being 105 sheared off by the lateral movement of heavy trains.

What is claimed is:—

1. A cement tie comprising a body, reinforcing fabrics embedded therein, and rein-

- forcing rods arranged in the body between the fabrics and projecting from the ends of the tie.
2. In a cement tie comprising a body, separated reinforcing fabrics embedded therein, reinforcing rods embedded in the body between the fabrics, and loops formed on the rods and extending beyond the ends of the tie.
3. A cement tie comprising a body, separated reinforcing fabrics embedded therein, reinforcing rods embedded in the body between the fabrics, and tapped members embedded in the body between the fabrics and lying against certain of the reinforcing rods.
4. In combination, a reinforced cement tie, tapped members embedded therein between the reinforcement, rail holding spikes threaded into the members, locking blocks carried by the ties, and means threaded into the members for holding the locking blocks in engagement with the spikes.
5. In combination, a reinforced cement tie, tapped members embedded therein between the reinforcement, rail holding spikes threaded into the plates, adjustable locking blocks carried by the ties, and means threaded into the members for holding the locking blocks in engagement with the spikes.

In testimony whereof I affix my signature in presence of two witnesses.

ABRAHAM EBERHART.
